IMMERSIBLE ELECTRICAL HEATER

Robert C. Belgau, Detroit, Mich.

Application July 5, 1945, Serial No. 603,341

12 Claims. (Cl. 219—41)

1

This invention relates to heating apparatus, and more particularly to electrical apparatus for heating liquids and solid materials, the heat units being generated at, or within, the process vessel.

In one form of the invention, the invention comprises a tubular heating device which is immersed in the product to be heated and includes means for vaporizing a liquid the vapors of which flow through a heat-radiating system, also immersed in the material, to transfer the heat of the vapors thereto.

There are many industrial processes wherein it is desired to heat a material at a rapid rate, while insuring that no part of the material is brought to a temperature which would produce burning or deterioration thereof. The requirement for accurately controlled heating means is especially stringent in the case of thermo-plastic compositions and foodstuffs, both of which deteriorate above a certain critical temperature.

Such materials have in the past been heated by various methods. One method comprises a central steam generating plant, utilizing coal or other fuel, to supply superheated steam to the various process tanks in which the products are heated. The temperature of the superheated steam may in such installations be accurately controlled, so as to limit the maximum temperature to which the material will be subjected; but where high temperatures are required as for many modern processes, the steam plant must be operated at correspondingly high pressures—upwards of 250 to 300 pounds per square inch. The high-pressure method is very costly and unsatisfactory in many cases, because in order to heat a single container, it is necessary that the entire steam generating plant be put into operation, with consequent excessive heating costs. Heat losses in conveying the high-pressure steam to the point of use are considerable, and the system as a whole lacks flexibility; the pumps, valves and accessories demand costly maintenance, and boilers must be periodically re-tubed, and fire-boxes rebuilt at great cost. Furthermore, where process vessels are fitted with steam-coils therewithin, a considerable amount of labor is required to disconnect and remove the coils when periodically cleaning the process vessel.

Combustion gases are being applied to the heating of a liquid heating medium at the site of use, the heating medium transferring its heat to the material being heated. This method is very satisfactory for many applications, but because of fire hazard it is not satisfactory or desirable for heating many inflammable products, or where, for other reasons, electricity is preferred, nor is it satisfactory for installations where flexibility is of primary consideration.

Electrical apparatus for heating the heat-

2

transfer medium, or for directly heating the material, is also being used, and generally consists of an electrical heating element which is immersed in the heating medium or liquid material in such manner that without the use of a circulating means, no effective circulatory action is obtained, so that burning of the material or a prolonged heating cycle may result; or by the use of stripheaters attached to the outside of the container, in such manner that a large proportion of the heat generated is radiated or transmitted to the container wall as ambient heat instead of direct heat. In any case where the heat is applied externally to the container, the container walls and external heating mass must, of course, be brought to a temperature above that to which the contents are being heated; and because the heat flows more readily within the metallic wall, in a direction parallel to the surfaces thereof, than directly through the wall at right angles to the surfaces, the diffusion prolongs the heating cycle with consequent increased heating costs.

In any of the systems just referred to, there is likely to be a considerable lag between the time when the heat supply is first turned on and the time when the heating area reaches its maximum safe potential, above that to which the product must be heated. Then, when the maximum operating temperature of the heating-mass is reached, and the current supply is turned off, heat units continue to flow from the higher potential into the product until the potential no longer exists, or until the current supply is again turned on. This is called "overshooting." The greater the heating mass the longer the time lags and the greater the degree of overshooting, with the result that it is difficult to maintain close temperature control. This is a very objectionable condition in applications where fluctuating temperatures are harmful to the product.

Furthermore, in applications where stripheaters are attached directly to the exterior walls of the product container, hot spots occur because of the difficulty in providing uniform heat distribution throughout the heated wall area.

In the present invention, the heat units are generated electrically at the site of use, and within the heating area which is submerged within, and in direct contact with, the liquid heating medium so that all heat units are directly transmitted thereto. As a portable immersion heating system the device is complete and independent of any other equipment, except for the vessel into which it can be immersed, and the only attachments to this device are the electrical cables which can be connected to the current supply by means of conventional male and female receptacles, thereby eliminating the dismantling labor usually required where other heating sys-

tems are employed. The electrical resistance elements are so arranged that they are immersed in the liquid heating medium and are of relatively small cross-sectional area with the total mass of the heating area being relatively small, thereby providing a rapid rate of heating, and of cooling, so that the objectionable lag and overshooting is reduced to a negligible amount. All heat units generated by the resistance elements are transmitted directly into the heating medium. A system of stacks, or baffle plates, induces a thermo-syphon action during the heating cycle and the heated medium is thus partially vaporized; and, in turn, transmits heat units to the material being heated.

An object of the present invention is to provide a heating device of simplified construction which will avoid the disadvantages of the prior art devices, in that it will be independent of other units and dependent only upon a supply of electricity at or within the process vessel.

A further object of the invention is to provide a heating unit which may be readily inserted in and removed from the container of material to be heated, and which may be used to supplement the stationary heating means usually connected to the container, so as to heat the material to the desired temperature quickly and uniformly with a minimum of current consumption.

A further object of the invention is to provide a heating unit which will transfer substantially all of the heat units directly into the material to be heated, the container for such material becoming heated only by the heated material rather than by the usual arrangement, wherein the heat is first transferred to the container walls and thence to the material.

A further object of the invention is to provide a heating unit which may be withdrawn and replaced as unit, for inspection and repair, or for cleaning the process vessel.

A further object of the invention is to provide a heating unit which may be immersed in the material to be heated, and wherein no part of the unit will be heated above a temperature representing the maximum degree to which the material may be safely subjected.

Further objects and advantages of the invention will be apparent from the following description, taken in connection with the appended drawings, in which:

Fig. 1 is a view in end elevation of a portable heating unit embodying the invention, the cover plate being removed to disclose the electrical connections;

Fig. 2 is a longitudinal section of the same, taken on the line 2—2 of Fig. 1;

Fig. 3 is a plan view of the same;

Fig. 4 is a sectional view of the vaporizing part of the apparatus, taken on the line 4—4 of Fig. 2 and with the heater elements removed.

Fig. 5 is a view in horizontal section of a heating cell which is a component part of the immersion heating system but modified and designed to be permanently installed in the vapor jacket of the vessel which contains the product to be heated;

Fig. 6 is a side elevation of the device shown in Fig. 5, with parts broken away to reveal the interior construction, and with the heater elements removed, but indicated by broken lines.

Fig. 7 is a fragmentary view in elevation showing a further modified arrangement of the electrical heating cell;

Fig. 8 is an end elevation of the apparatus shown in Fig. 7; and

Fig. 9 is a diagrammatic representation of the electrical control means of the heating unit.

Before explaining in detail the present invention it is to be understood that the invention is not limited in its application to the details of construction and arrangement of parts illustrated in the accompanying drawings, because the invention is capable of other embodiments according to the size, shape and other requirements to accommodate various applications. Also it is to be understood the phraseology or terminology employed herein is for the purpose of description and not of limitation.

The apparatus shown in Figs. 1—4 comprises a cylindrical tank 10 having an end wall 12 of dished shape, being preferably welded in place and designed to resist pressures, either superatmospheric or subatmospheric, existing within the tank. The other end of the tank is closed by means of an end wall 14 which has formed therein, preferably by welding, or casting, a chamber 16 which serves to house the terminal ends of the electrical heating elements and their connections. The chamber 16 is formed of a cylindrical wall 17 and an inner wall 19, and is sealed by means of a gasket and cover plate 18 securely held in position against end wall 14 by means of studs 20, secured in the wall 14 and provided with nuts 22.

A plurality of tubular sheaths 24 extend horizontally through the inner wall 19 of chamber 16, one end of each sheath being fixed in place in apertures in said wall by welding or other means. The forward, or open, end of each of the sheaths 24 extends through the wall 19 into the chamber 16, to permit insertion into the sheaths of electrical resistance elements 26, of a conventional type, each having both terminals at one end thereof, to accommodate electrical terminals 27. Leads 28 interconnect the terminals 27 and extend through a pair of cables 30 to connect to a source of current supply, not shown. The rear ends of sheaths 24 are closed by caps 32, so that liquid within the tank 10 cannot enter the sheaths.

Supported centrally within the tank 10 and secured in any convenient manner, as by tack-welding to wall 19, are a plurality of vertical vanes or baffle-plates 34 which extend centrally and longitudinally between the sheaths 24 so as to direct the flow, by thermo-syphon action of the heating medium contained in the tank 10, upwardly over the heated sheaths, thus tending to heat the liquid quickly and uniformly and at the same time maintaining a cooling effect on the heated sheaths. The baffle plates 34 are joined together by upper bars 36 and lower bars 38 to form a rigid grid, the two lower sets of bars being spaced from each other by central baffle plates 40 which extend somewhat beyond the other baffle plates 34 toward the bottom of the tank 10.

The heating medium 42 contained in tank 10 is maintained at a normal liquid-level indicated at 44, above the upper-most of the sheaths 32. The heating medium may be water, Prestone, mercury, alcohol, non-volatile oil, diethylene glycol, Dowtherm or the like, having suitable characteristics to accommodate the desired operating temperature according to the requirements of the application. The space within tank 10 above the liquid level 44 is herein referred to as the vapor chamber 45.

The upper surface of tank 10 is provided with an aperture within which is welded a pipe nipple 46, internally threaded to receive a threaded pipe

plug 48 which is provided with a metallic tube 50 to serve as a means for exhausting all free air from the system, and which is crimped as indicated by numeral 52 to form a hermetic seal. By means of this seal, the free air may be exhausted by a vacuum pump or by heating the tank until the evolution of vapors from the heating medium drives the free air out through the tube 50, whereupon the end 52 is crimped to seal the system against re-entry of air. After such removal of the free air, the pressure within tank 10 at room temperature will be materially below atmospheric, corresponding approximately to a 28 inch vacuum, so that in the normal operation of the device the absolute pressure within the tank will be less than fifteen pounds per square inch. The lowering of the vapor pressure within the system also lowers the boiling point of the heating medium, and otherwise assures better performance. This feature is of considerable importance, because many states require that a licensed engineer be present at all times during the operation of any heating system wherein the normal operating pressure exceeds fifteen pounds per square inch. The present device is designed to employ heating mediums which boil at 350° F. to 500° F., so that the operating pressure, even at temperatures of 400° F. to 500° F., are below fifteen pounds and such engineer's presence is not required.

A vertical conduit 54 extends upwardly from the chamber 16, being secured in apertures in the upper walls of the chamber 16 and of the tank 10, as by welding. This conduit accommodates the electrical cables 30, which pass upwardly in the conduit and out through an outlet 56 extending horizontally therefrom at a point near the upper end of the conduit.

At its upper end, conduit 54 is provided with a mounting flange 58, secured thereto as by welding, and through the flange extends a pressure transmitting tube 60. A sump 62 is secured to the under surface of the mounting flange through which the tube 60 extends as shown in Fig. 2. The heating medium enters the sump by means of a tube 64, the lower end 65 of which extends through an aperture in the wall 19 of the chamber 16 in such position as to open immediately below the normal liquid level in the tank 10. The upper end of tube 64 extends into and terminates adjacent the upper portion of the sump, well above the lower end of tube 60, the arrangement forming a liquid trap to insure that the vaporized medium will not enter into the pressurestat, which would be damaged by the vapor temperature.

A conventional pressurestat is mounted upon flange 58 with a suitable gasket therebetween to assure a leak-proof seal, and is anchored in place by means of bolts 66. A tubular portion 68 connects with pipe 60 and with body 70 of the instrument. Body 70 contains a mechanism of conventional construction, shown diagrammatically in Fig. 9 as comprising a diaphragm 71 which is responsive to pressures within the vapor chamber 45. Increase of such pressures beyond a predetermined value set by adjustment of the knob 74 causes a switch 73 in a relay circuit 75 to be opened, thereby deenergizing the relay and opening a switch 77 in the main circuit formed by leads 28. Opening switch 77 deenergizes the main circuit and cuts off the supply of electricity to the resistance elements 26 until the pressure within the pressurestat has fallen to a point where the switch 73 will again be closed. The

supply of current to resistance elements 26 may also be controlled manually, by means of a manual switch 79. The adjustable knob 74 is provided at the top of the pressurestat to enable the operator to adjust the instrument for the desired operating temperature. The pressurestat may be of conventional construction; and because such construction is well known, it is not further described herein.

The heating unit thus far described is designed to be placed in a process tank 76 to heat the contents thereof, which may be a thermoplastic composition, foodstuffs, or any other type of product which is to be processed. The location of the outlet 56 is preferably so arranged that the heating unit may be suspended within process tank 76 and submerged within the product therein, with outlet 56 positioned above the tank sides to permit the leads 28 to pass from the outlet to a source of current supply, as to a switch upon an adjacent wall. The lower side of outlet 56 may be provided with a bracket 69 which rests upon the upper edge of the container to support the heating system so that it clears the bottom of tank 76. A bracket 78 may likewise be attached to the radiating tube 82 to provide a means for supporting one end of the heating unit, and rests upon the top sides, or ends, of the process tank with the heating unit suspended in the tank and with all heated areas well submerged within the product being heated. The level of material in tank 76 is indicated at 85. This construction permits of instant removal of the heating unit from the process tank without breaking any connections and whether the heating unit is hot or cold.

A plurality of radiating tubes 80, 81, 82 of any suitable size or shape are connected to the interior of tank 10 and extend upwardly therefrom in such relation as to be entirely immersed in the material being heated. Each of the tubes 80, 81, 82 is provided with a vapor inlet 84 connecting to the vapor space within tank 10, adjacent the uppermost portion thereof, and with a liquid outlet 86 which extends downwardly into tank 10 to a point well below the liquid level 44 therein. The radiating tubes operate in a manner similar to that of steam radiators, conducting the vaporized heating medium to the upper portion of the tube where the heat of vaporization is dissipated into the product, and the resultant condensate returns by gravity to the bottom of the tank 10 to be again vaporized.

In the form of the invention thus far described, the heated areas of the apparatus are entirely immersed in the product to be heated, so that very few heat units are lost by radiation and the heating cycle is greatly reduced, because any product can be more quickly heated from within than by the application of heat from the outside surfaces. This form of the invention may be used to advantage in installations wherein the process tank, indicated at 76, has no heating means permanently connected thereto, or in which the container has permanently connected heating means which is not adequate to bring the material up to temperature quickly enough, as in resuming operations after a shut-down. If for example, the tank 76 contains thermo-plastic material which becomes solid at room temperatures, the portable apparatus disclosed in Figs. 1 to 4 may be placed in the tank before a shut-down and turned off by means of the manual switch 79. Upon resuming operations after the shut-down, the current may be turned on and the normal

heating means likewise turned on to bring the material up to the desired temperature within a minimum length of time. As a further means of utilizing the heating apparatus of this type, it may be placed in the process tank prior to a shut-down, and the regulator knob 74 set to maintain a relatively low temperature below the normal operating temperature, so that a correspondingly shorter period of time will be required to bring the material up to operating temperature when operations are resumed, while not causing deterioration of the material such as occurs if it is maintained over too long a period of time at higher temperatures. Regardless of how the device is used, it will be noted that no part of the apparatus is brought to a temperature above the predetermined critical temperature at which burning or degradation of the material occurs, since the very high temperatures which may exist in the resistance elements 26 can be transmitted to the material only through the heating medium, the temperature of which is controlled by the pressurestat 10; or by radiation or conduction to the cover plate 18, which is so spaced from the ends of the resistance elements 26 that its temperature will not exceed the controlled temperature of the heating medium within the tank 10.

For installations wherein it is desirable to mount the heating device fixedly in a container of liquid to be heated, the form of the invention shown in Figs. 5 and 6 may be employed. In this form of the invention, the plate 88 corresponds to the end wall 14 in Figs. 1 to 4, and the chamber 90 is similar to chamber 16 in those figures. The plate 88 is secured as by welding to the vertical wall of the process tank, indicated at 92, adjacent the bottom thereof, and is provided with threaded studs 94 for securing on the outside of the tank an electrical outlet box 96, of conventional construction. A pipe 98 leads through an aperture in the cylindrical wall of the outlet box, and contains the usual electrical leads 102, which are connected to the resistance elements 100 in the manner described in connection with Figs. 1 to 4. The electrical leads for the resistance element are indicated only diagrammatically at 102 in Figs. 5 and 6, the electrical connections and pressure control being similar to those shown in Figs. 1, 2 and 9.

The resistance elements 100 are slidably encased in sheaths 104, which are closed at their inner ends by caps 106 in the same manner as described in connection with caps 32 in Figs. 1 to 4, to seal the resistance elements against contact with the liquid being heated. In order to direct the circulation of the liquid about the sheaths 104, a plurality of vertical baffle members 108, 109 are interposed between the various sheaths 104, and held in assembled relation by upper and lower bars 110, 111. The bars 111 are flanged and welded to the baffle members 109, which extend downwardly below the lower edges of baffle members 108, in order that the resulting grid of baffle members will conform generally to the cylindrical shape of the chamber 90. An end plate 114 is secured as by welding to the ends of the baffle members, to provide better thermo-syphon action of the heating medium.

The form of the invention shown in Figs. 7 and 8 is similar to that shown in Figs. 5 and 6, and the parts are designated by similar reference numerals, except that in Figs. 7 and 8 the chamber 90 is omitted, the sheaths 104 being secured to a plate 116 welded over an aperture in the tank 75

92, with the terminal ends of the resistance elements 100 extending into outlet box 96. This arrangement permits some loss of heat through the outlet box, but is cheaper to manufacture and install than the other forms of the invention disclosed herein.

Either of the forms of the invention disclosed in Figs. 5 to 8 is suitable for use in fixed installations in which the tank 92 serves as a jacket around the vessel containing the product, and the jacket-space contains a heating medium of the nature referred to above. The tank 92 may be hermetically sealed, and designed to transmit heat from the heating medium to the material to be processed, in the manner described in my co-pending application Serial No. 603,776, filed July 9, 1945, now Patent No. 2,437,453, issued March 9, 1948.

The forms of the invention shown in Figs. 5 to 8 may also be used where the material to be processed will not be injured by overheating, or where the danger of overheating is slight, and where the heater tubes will be always submerged in the said material.

Although the invention has been described with particular reference to certain embodiments thereof, it may be embodied in other forms and is therefore not limited to the forms disclosed, nor otherwise, except in accordance with the language of the appended claims.

I claim:

1. Apparatus for heating material in a container, comprising a tank, liquid heating medium therein, electrical resistance elements extending within said tank for heating said medium, pressure responsive means operative upon the occurrence of a predetermined maximum pressure to deenergize said resistance elements, radiating elements connected to the interior of said tank for transmitting heat from the vaporized heating medium to the material in the container, a conduit leading from said resistance elements to a point above the normal level of material in the container, electrical connections extending through said conduit to said resistance elements, and means associated with said conduit for suspending the heating apparatus in the container in spaced relation from the walls thereof.

2. Portable heating apparatus for material in a container, comprising a sealed evacuated tank, a vaporizable heating medium in said tank, said heating medium having such vapor tension relative to the degree of evacuation as to produce subatmospheric pressures in the tank at room temperatures and superatmospheric pressures at normal operating temperatures of the apparatus, reentrant members extending into the interior of the tank, electrical heating means removably mounted in said reentrant members for heating the heating medium, means for transmitting heat from the heating medium to the material in the container, a conduit fixed to said tank and extending above the container, a pressure-responsive device mounted on said conduit, means in said conduit for transmitting pressures from the interior of the tank to the pressure responsive means, and electrical connections extending from said heating means through said conduit and controlled by the pressure-responsive means.

3. Heating apparatus comprising a container for material to be heated, means in a wall of said container forming a reentrant recess, a plurality of reentrant members communicating with said recess and extending into the interior of the container, a plurality of baffle members interposed

between said reentrant members, electrical resistance elements removably mounted in said reentrant members for transmitting heat therethrough to the material to be heated, electrical terminals for said resistance elements in said recess, an electrical outlet box mounted exteriorly of said container in juxtaposition to said recess, and electrical connections extending from said terminals through said outlet box.

4. The invention defined in claim 3, wherein the baffle members are formed as a grid and secured in spaced relation by means of transverse members welded thereto at intervals along their length.

5. Heating apparatus for material in a container, comprising a sealed tank adapted to be submerged in said material, means for suspending said tank from the container walls in spaced relation thereto, a vaporizable liquid heating medium occupying a portion of the space in said tank, said tank being exhausted of gases to produce subatmospheric pressures therein at room temperatures, electrical heating means in heat-exchanging relation to said heating medium and spaced from the walls of said tank, means responsive to pressures generated by said heating medium for controlling said heating means, and radiating tubes connected to the interior of said tank and extending within said material for receiving vaporized heating medium therefrom and transmitting heat to said material, said suspending means including a rigid conduit fixed to said tank and extending above the normal level of material in the container, and means associated with said conduit for engaging the upper edge of said container.

6. The invention defined in claim 5, wherein said radiating tubes are provided with inlets connected to the interior of said tank above the normal level of heating medium therein, and outlets connected below the normal level of heating medium therein.

7. Apparatus for heating material in a container, comprising a sealed tank adapted to be immersed in said material, means for suspending said tank from the container walls in spaced relation thereto, a vaporizable liquid heating medium in said tank, a plurality of horizontally extending electrical heating elements in heat-exchanging relation to the heating medium in said tank, said elements being arranged in staggered relation and spaced from each other and from the walls of said tank, a plurality of vertical baffles interposed between said heating elements to facilitate circulation of heating medium past said heating elements, and radiating elements connected to the interior of said tank and extending within said material for receiving vaporized heating medium therefrom and transmitting heat to said material.

8. The invention defined in claim 7, comprising in addition means responsive to pressures generated by said heating medium for controlling said heating elements.

9. The invention defined in claim 7, wherein the heating medium occupies but a portion of the free space within said tank, and said tank is provided with an aperture for evacuating gases from the tank, and a check valve in said aperture for preventing reentry of gases therethrough.

10. Heating apparatus comprising a cylindrical tank having a convex end wall and a recessed end

wall, a cover plate closing the recess in the recessed end wall, reentrant members extending from said recess to the interior of the tank, electrical heating elements removably mounted in said reentrant members, liquid heating medium in said tank covering said reentrant members to receive heat therefrom, a conduit leading from said recess through the cylindrical wall of said tank, electrical connections extending through said conduit and connected to said heating elements, a pressure-responsive device mounted on said conduit and controlling said electrical connections, a duct connecting the interior of said tank with said pressure-responsive device, said duct including a liquid trap, and a radiating element comprising a tube having one end connected to the interior of the tank at a point above the liquid level therein and its other end connected to the tank at a point below the liquid level therein, to form a closed circulatory system.

11. Heating apparatus comprising a cylindrical tank having a convex end wall and a recessed end wall, a cover plate closing the recess in the recessed end wall, reentrant members extending from said recess to the interior of the tank, electrical heating elements removably mounted in said reentrant members, liquid heating medium in said tank covering said reentrant members to receive heat therefrom, a plurality of baffle members in said tank for inducing movement of said liquid heating medium past said reentrant members by thermo-syphon action, a conduit leading from said recess through the cylindrical wall of said tank, electrical connections extending through said conduit and connected to said heating elements, a pressure-responsive device mounted on said conduit and controlling said electrical connections, and a duct connecting the interior of said tank with said pressure-responsive device, said duct including a liquid trap.

12. Heating apparatus comprising a cylindrical tank having a recessed end wall, a cover plate closing the recess in the recessed end wall, reentrant members extending from said recess to the interior of the tank, electrical heating elements mounted in said reentrant members, liquid heating medium in said tank covering said reentrant members to receive heat therefrom, a conduit leading from said recess, electrical connections extending through said conduit and connected to said heating elements, a device connected to and responsive to conditions within the interior of said tank and controlling said electrical connections, and a radiating element comprising a tube having one end connected to one end of the tank at a point above the liquid level therein to form a closed circulatory system.

ROBERT C. BELGAU.
